UNITED STATES PATENT OFFICE.

WALTHER BURSTYN, OF BERLIN, GERMANY.

WIRELESS-TELEPHONE TRANSMITTER.

1,148,827.

Specification of Letters Patent.

Patented Aug. 3, 1915.

Application filed March 25, 1909. Serial No. 485,775.

To all whom it may concern:

Be it known that I, WALTHER BURSTYN, a subject of the Emperor of Austria-Hungary, and a resident of Berlin, Germany, 5 have invented a new and Improved Wireless-Telephone Transmitter, of which the following is a specification.

Diaphragm condensers have previously been used in wireless telephony instead of 10 microphones, the diaphragm being influenced either directly or indirectly by the sound; in the latter case the diaphragm consists of iron, being at the same time the diaphragm of a magnet telephone. However, 15 it is not possible to produce by means of a single diaphragm a condenser which is able to follow the acoustic vibrations and to carry a sufficient energy. Therefore it would be necessary to divide the diaphragm into several 20 portions. But this division is impossible, for acoustic reasons (interference), if the diaphragm is directly influenced by the sound, and it would be too complicated in the second case.

According to my invention the diaphragm 25 is also influenced indirectly by the sound, not by magnetic forces, but by electro-static ones.

Figure 1 shows in sectional elevation one 30 construction of multiple diaphragm condenser suitable for the purpose of the present invention. In a cylindrical box z of ebonite or similar material, two series of thin metal disks a , b are inserted, the disks 35 a being insulated from the disks b and being connected together and to a terminal p' , while the disks b are similarly connected together and to the terminal p^2 . As shown in the drawing, the disks are arranged in 40 pairs, two of one series being followed by two of the other series, except in the case of the terminal disks, and successive disks are spaced apart by interposed rings which in the case of disks of the same series a , a or b , 45 b are of metal as indicated at l , and in the case of disks of different series a , b are of insulating material as indicated at r . The assembled disks and spacing rings are tightly clamped as by means of a screw.

Fig. 2 shows another arrangement. Here 50 each second disk of condenser v is not a thin diaphragm, but a solid plate. The diaphragms a are all connected together and with the terminal k' , the rigid disks c and d 55 are alternately connected together and with the terminal k^2 and k^3 . In this embodiment,

the disks are compressed for example by means of a central screw, passing through a hole in each disk, without touching the disks.

Fig. 3 shows one method of using the diaphragm condenser for wireless telephony purposes. Here f is the aerial wire; inserted in it is the coil c^2 which is loosely coupled with the coil c' , the latter carrying electrical oscillations, produced by a high frequency 60 dynamo g or a Poulsen arc or some other generator of continuous oscillations; z is the diaphragm condenser, s s are choking coils, 65 y is an additional battery, such as used for condenser telephones, but not absolutely necessary, t is a telephone induction coil, m is a microphone, e the battery for same, all the 70 above being connected as shown.

Assuming the aerial wire to be at the start in resonance with the primary oscillations; if one speaks in the microphone, the induced currents charge the diaphragm condenser, its diaphragms a attract the diaphragms b , the capacity of the diaphragm condenser is altered, hence the tuning of the 75 aerial wire, the latter consequently absorbing less current than before. These variations, being in correspondence with the sound received by the microphone, can be heard in the receiving station, by means of 80 a thermodetector, as a sound equivalent to the primary one.

Fig. 4 shows a scheme which may be used with the diaphragm condenser of Fig. 2. That part of the diaphragm condenser lying 85 between the terminals k' and k^2 is inserted in the aerial wire, while the part lying between the terminals k' and k^3 is connected with the telephone induction coil t . Assume the antenna being at the start out of 90 resonance with the primary oscillations; if one speaks on the microphone, the condenser k' k^3 is charged more or less; the diaphragms alter by their movements the capacity of the condenser k' k^2 , therefore the 95 tuning of the aerial wire, the latter consequently absorbing more or less current of the high frequency circuit. Of course other schemes may also be used besides those shown in Figs. 3 and 4.

In order to increase the electric resistibility of the diaphragm condenser, its dielectric may consist of hydrogen or similar gases instead of air. Also the mechanical construction may be varied.

I claim:

1. In a system of influencing a rapidly al-

ternating current by sound, especially for the purposes of wireless telephony, means for producing rapidly alternating currents in a circuit, a diaphragm condenser with 5 a gaseous di-electric operatively connected with said circuit, means for producing electrostatic forces acting upon the condenser and means for varying these electrostatic forces by sound waves, substantially as described.

2. In a system of influencing a rapidly alternating current by sound, especially for the purposes of wireless telephony, an aerial circuit, a source of rapidly alternating current 15 and a diaphragm condenser having a plurality of diaphragms, both operatively connected with the said circuit, means for producing electrostatic forces acting on the diaphragms, and means for varying these electrostatic forces by sound waves, substantially as described.

3. In a system of influencing a rapidly alternating current by sound, especially for the purposes of wireless telephony, means 25 for producing rapidly alternating currents in a circuit, a diaphragm condenser consisting of a plurality of condensers with a gaseous dielectric containing hydrogen, each 30 of such condensers having a movable diaphragm and a rigid plate, means for producing electrostatic forces acting on the diaphragms, and means for varying these electrostatic forces by sound waves, substantially as described.

35 4. In a system of influencing a rapidly alternating current by sound, especially for the purposes of wireless telephony, means for producing rapidly alternating currents in a circuit, a diaphragm condenser consisting 40 of a plurality of condensers with a gaseous dielectric containing hydrogen, each of such condensers having a movable diaphragm and a rigid plate, means for pro-

ducing electrostatic forces acting on the diaphragms, and a circuit connected with the 45 condenser and containing a microphone whereby the said electrostatic forces can be varied by sound waves.

5. In a system of influencing a rapidly alternating current by sound, especially for 50 the purposes of wireless telephony, an aerial circuit, a multiple diaphragm condenser connected with the aerial circuit, an electric circuit connected with the diaphragm condenser and adapted to be influenced by sound 55 waves, means associated with said circuit for producing electrostatic forces acting upon the condenser, and means in said electric circuit whereby these forces and the capacity of the condenser can be varied indirectly by 60 sound waves, substantially as described.

6. In a system of influencing a rapidly alternating current by sound, especially for the purposes of wireless telephony, an aerial circuit, an electric circuit associated therewith adapted to be influenced by sound waves, and a diaphragm condenser having as one element a vibratory disk and as another element a rigid plate, these elements being connected with the sound wave influenced circuit so that variations of current therein will cause movement of the diaphragm, and a second rigid plate which, together with the diaphragm, is connected with the aerial circuit so that the aforesaid 70 movements of the diaphragm will alter the capacity of the said aerial circuit, substantially as described.

In witness whereof I have hereunto set my hand March, 1909, in the presence of two 80 subscribing witnesses.

WALTHER BURSTYN.
